PREPARATION OF PIEZOELECTRIC RESONATORS

Roland H. Broseker, Anne Arundel County, and James L. Hessenauer, Baltimore, Md., assignors to Bendix Aviation Corporation, South Bend, Ind., a corporation of Delaware

Application October 6, 1942, Serial No. 461,015

8 Claims. (Cl. 88—14)

1

This invention relates to the manufacture of piezo-electric resonators and more particularly to an improved method and apparatus for determining the cutting planes to be used in the preparation of such resonators.

It is well known that piezo-electric quartz elements are excellently suited for the construction of very stable vacuum tube oscillators, and that the degree of immunity to frequency variations caused by temperature changes is largely determined by the angular relation between the surfaces of the resonating element and the axes of the mother crystal from which the element is cut. Certain angles must be very carefully controlled during the preparation of the crystal resonator if the desired low temperature coefficient is to be realized. Two of the more popular cuts are: the AT cut in which the major plane surface of the resonator element makes an angle of 35 degrees, 22 minutes with the Z or optical axis; and the BT cut in which the major plane surface of the resonator element makes an angle of 49 degrees, 47 minutes with the Z axis. Quartz is termed right or left-handed depending on the direction in which the plane of polarization of plane polarized light is rotated upon traverse of a given sample, and it has been found that the cutting angles must be measured in one direction from the reference axis for right-handed quartz and in the other direction for left-handed quartz. Initially, these cutting angles were determined by measurements from an intact reference face on the mother crystal, by measurements from the optical axis as determined by observation under convergent polarized light or by the use of X-rays.

More recently there has been described a method of determining the cutting plane to be used in the preparation of bar stock for crystal blanks in which the mother crystal is first cut into slabs employing cutting planes parallel to the Z axis and to the Y or mechanical axis. These pieces are next etched in hydrofluoric acid, washed, dried, and illuminated by the light emanating from a small pinhole and traversing the piece in a direction substantially perpendicular to the optical axis. With a positive electric face adjacent the pinhole, a parallelogram may be seen when the emergent face of the slab under test is viewed, and it has been found that the direction of the short side of this parallelogram corresponds to that of the optical axis, while the long side of the parallelogram is inclined to this axis at an angle of approximately 51 degrees, 46 minutes. The method of deter-

2

mining the positions of the cutting planes to be employed in the preparation of bar stock for crystal blanks having predetermined characteristics, utilizing the sides of the parallelogram as references, is described in a United States patent application filed August 10, 1942, Serial Number 454,284 by R. H. Broseker et al., in which the marking of the quartz slabs with guide lines established by reference to the sides of the above parallelogram is detailed. While this method of marking represents a considerable advance over the methods which previously found wide employment, a certain amount of mechanical skill and ability to judge the parallelism of the marking straight edge with the reference side of the parallelogram is still required. Furthermore, it was necessary to move not only the marking edge but also the quartz slab for each additional guide line required for the marking off of a number of bars on a given slab.

One of the principal objects of this invention is to provide new and novel apparatus for the more rapid and accurate determination of cutting planes in piezo-electric materials.

Another object of the invention is to reduce the amount of labor required for the marking of a plurality of cutting guide lines on a slab of crystalline piezo-electric substance.

Still another object of the invention is to provide improved apparatus for the establishment of cutting lines for piezo-electric crystal blanks in which correct orientation of the work piece is indicated by interlocking patterns.

A further object of the invention is to provide new and novel apparatus in which a slab of piezo-electric material may be visually oriented for marking cutting guide lines with improved accuracy and increased speed.

The above objects and advantages of the invention are accomplished by locating a properly prepared quartz slab adjacent two illuminated pinholes, observing the light patterns appearing in the emergent face of the slab, orienting the slab under test so that the adjacent patterns interlock and marking the quartz with a line drawn along one edge of a guide triangle whose base is held in contact with a guiding plane fixed with respect to a line passing through the two illuminated pinholes. Where more than one guide line is desired, the additional lines may be drawn parallel to the original line by sliding the triangle back and forth along the guiding plane.

Other objects and advantages of the invention will in part be described and in part be

obvious when the following specification is read in conjunction with the drawing in which:

Figure 1 is a view of the completed apparatus in perspective.

Figure 2 is a cut-away side elevation showing the internal construction.

Figure 3 is a top view with the test piece removed showing the work table.

Figure 4 illustrates the patterns seen with the test piece improperly oriented.

Figure 5 illustrates the patterns seen when the test piece is properly oriented.

Figure 6 is a top view showing one of the guide triangles in detail.

Referring in greater detail to Figure 1, the completed apparatus is seen in perspective with the sheet metal box 1 provided with the work plate or table 2. Located within the box 1 is an electric light bulb controlled by the on-off switch 3 and receiving power through a line cord 12. The top and bottom edges of the box 1 are provided with a number of holes 4 to provide for convectional dissipation of the heat generated by the bulb within the box 1. Located along the rear surface of the work table 2 is the guide bar 5 which may be referred to as the BT guide, while a guide bar 6 is located along one of the short edges of the work table 2 perpendicular to the BT guide and will henceforth be referred to as the AT guide. The quartz slab 7 which is to be tested, is located on the work table 2 where it is traversed by the light emanating from two spaced pinholes in the table 2, and this light produces patterns in the emergent face of the slab 7 which will be more completely described and discussed in connection with a later figure. While observing these patterns, the observer manipulates the slab 7 on the work table until the two patterns interlock and, leaving the slab in this position, a triangular shaped marking guide 8 is placed over the quartz slab in the position shown with the extended base 9 thereof maintained in close contact with the guiding surface of one of the guide bars 5, 6. In Figure 1, the apparatus is set up preparatory to marking the guide lines on the slab 7 which will indicate the cuts to be made for the preparation of bar stock for the manufacture of BT cut blanks. When preparing AT bar stock, the guide bar 6 is used as a reference and the triangular shaped marking guide is of somewhat different dimensions than those employed in the BT triangle. After marking, the slab 7 is cut up into a number of parallel sided bars using a suitable saw, and the bar stock thus produced is cut up into crystalline plates or blanks employing a cutting plane normal to the longitudinal axis of the bar. The blanks are then finished to the desired frequency in the usual manner.

Details of the apparatus are more clearly seen in Figure 2, showing the lamp 10 mounted in the socket 11 within the box 1 and connected to the line cord 12 and the on-off switch 3 in series relationship. The work table 2 is supported on the formed edges at the top of the box 1 and is provided with two pinholes or apertures 13 approximately .013 inch in diameter spaced by about $\frac{3}{8}$ inch located over the light source 10. The quartz slab 7 is placed on the work table 2 directly over the apertures with the negative end of the X-axis up and is rotated by the operator to such a position that the desired images are visible in the emergent face 14.

The position of the pinholes 13 with respect to the guide bars 5 and 6 is most clearly seen

in the top view of Figure 3 in which the slab under test has been removed. Here, the work table 2 with the guide bars 5 and 6 located along two of its edges is viewed from the top, showing the apertures 13 defining two points on a line substantially parallel to the BT guide 5 and located directly over the light source 10.

Quartz slabs which are to be marked on this apparatus must be prepared in the proper manner. The slabs are cut out of the mother crystal using cutting planes spaced by about $\frac{3}{4}$ inch parallel to the Y and Z axes, etched for a period of three to four hours in a 48% solution of hydrofluoric acid and then washed and dried. The light emanating from the pinholes therefore traverses the test slab in a direction perpendicular to the Y and Z axes and parallel to the X or electrical axis. As described in the aforementioned application, each pinhole gives rise to a parallelogram shaped image in the emergent face of the slab when that face is at the negative end of the X axis, and produces a double ended arrow as an image when the emergent face is at the positive end of the X axis. The apparatus described so far is intended to function with the negative face of the crystal slab toward the observer, that is, with parallelogram shaped images.

The images appearing in the emergent face 14 of the slab 7 are shown in Figures 4 and 5 for two conditions; in Figure 4, the patterns 15 indicate that the slab is improperly oriented for the marking operation, while the interlocking images 16 of Figure 5 illustrate the relationship observed when the slab 7 has been oriented to the proper position. In each of these figures, the location of the pinhole is indicated at 16, and it has been found that each of the figures 15 rotates about the point 16 as a center when the slab is rotated. When the figures are of the proper size, the perfection of interlocking can be observed with great accuracy as is clearly seen in Figures 4 and 5. When the figures are interlocked as in Figure 5, the crystalline molecular planes parallel to the optical axis within the slab under test make an angle of approximately $51^\circ 46'$ with a line through the centers of the individual figures and consequently with the line defined by the two apertures. As the BT guide 5 is substantially parallel with the line defined by the two apertures, adjustment of the slab to cause the figures to interlock places the optical axis at the predetermined angle of $51^\circ 46'$ to the guide bar 5 and permits the use of the triangle 8 to inscribe the cutting guide lines on the slab 7. For best results, it has been found that the two images should overlap only slightly, and as the size of the image is determined by the distance between the pinhole and the emergent face, the slab thickness thereby controlling the image size, it has been found that the optimum separation of the two pinholes varies with the thickness of the slab to be tested. A pinhole separation equal to approximately one-half the thickness of the test slab has yielded highly satisfactory results.

With the slab in such a position that the interlocked images of Figure 5 are seen, the triangle of Figure 6 is placed over the top surface of slab 7 with the base 9 thereof in contact with the BT guide 5 and a marking pencil drawn along the edge of triangle 8 marked "L". The triangle may now be moved laterally a distance equal to the desired width of the bar stock and another line scribed, the process being repeated until the entire slab is marked off for cutting into bar stock preparatory to the blank cutting. Thus, once the

crystal slab 7 has been orientated to the proper position, the guide lines may be scribed on the surface thereof in any desired number without subsequent movement and the thereby necessitated reorientation of the slab. This results in a marked reduction in the time consumed for the performance of the marking operation as only the triangle need be moved, and its orientation is always fixed by the presence of the guide 8; whereas in the former performance of this operation, it was necessary to move the slab and reorientate it each time. Triangle 8, utilized for the marking of BT bar stock, is an isosceles triangle having an apex angle A of 3 degrees, 58 minutes. The "R" and "L" markings along the triangle edges indicate the edge to be used as a marking guide for right-handed and left-handed quartz respectively. The optical rotatory polarity of the quartz slab under test is readily determined by inspection of the parallelogram diagrams. The quartz sample is first rotated so that the long sides of the parallelogram are parallel to the BT guide 8 and the slope of the short side of the parallelogram then indicates the sign of the rotatory polarity. When the short side slopes to the right, the slab under test is right-handed quartz as is indicated by the marking at the lower right-hand corner of the work table 2, while the left-hand slope shown in Figure 5 indicates left-handed quartz.

Bar stock for the manufacture of AT cut crystal blanks is prepared in a manner similar to that above outlined, except that the AT guide 6 is used as a reference and the guide triangle used has an apex angle of approximately 5 degrees, 44 minutes. The "L" and "R" are placed along the guide edges of the AT triangle in the same position as shown in Figure 6.

The apparatus described utilizing two spaced pinholes suffices to illustrate the principle of the invention, and with this in mind, it is seen that a number of holes arranged in a straight line or any desired geometric pattern may be used to provide more of the same kind of images or to indicate correct orientation by a somewhat different final pattern. Further, it is clear that either the long sides of the parallelograms or the double-ended arrows produced with the positive face adjacent the observer may be employed to indicate orientation if the angle between the line defined by the apertures and the legs of the triangular guide is altered to suit.

It will be obvious that many changes and modifications may be made in the invention without departing from the spirit thereof as expressed in the foregoing description and in the appended claims.

We claim:

1. The method of inscribing cutting guide lines on a slab of piezo-electric quartz having substantially parallel opposite etched principal faces parallel to the Y and Z axes which comprises, passing two spaced beams of light through said slab substantially normal to the incident face, orientating said slab to cause the light patterns produced in the emergent face of said slab by said beams to interlock, and marking said slab with a line making a predetermined angle with the line determined by said beams.

2. The method of inscribing cutting guide lines on a slab of piezo-electric quartz having substantially parallel opposite etched principal faces parallel to the Y and Z axes which comprises, passing a plurality of spaced beams of light through said slab substantially normal to the

incident face, orientating said slab to cause the light patterns produced in the emergent face of said slab by said beams to interlock and marking said slab with a line making a predetermined angle with a line determined by two of said beams.

3. In apparatus for the determination of cutting-planes in piezo-electric quartz: a light source; an opaque plane structural member provided with a plurality of spaced apertures adjacent said light source; a guide member having a plane reference surface, said guide member being so mounted with respect to said structural member that said reference surface extends on the side thereof opposite said light source; and a cutting-plane determining means movable along and in contact with said reference surface, said means having a straight edge extending across said plane structural member in a direction along which the piezo-electric frequency response of a quartz sample will undergo a minimum variation with temperature change, when said sample is in the form of an etched slab with its major faces parallel to its Y and Z axes and is placed against said plane structural member and said apertures, and is of such thickness and so orientated that quadrilateral light dispersion patterns formed in said sample by light emerging from said apertures are interlocked by linear fusion of their adjacent sides.

4. In apparatus for the determination of cutting planes in piezo-electric quartz: a light source; a light screen provided with two spaced apertures adjacent said light source; and an element having a plane guide surface, said element being so mounted with respect to said light screen that said plane guide surface extends in substantial parallelism with, in facing relation to, and on the same side of said screen as the light beams emanating from said apertures, whereby; an etched slab of piezo-electric quartz having its major faces parallel to its Y and Z axes and a thickness equal to substantially twice the spacing of said apertures may be placed against said screen and said apertures, and so orientated that quadrilateral light dispersion patterns produced therein by said light beams interlock by linear fusion of their adjacent sides, whereupon the lines in said quartz along which piezo-electric frequency response undergoes a minimum of variation under changes of temperature extend in fixed and pre-chosen directions with respect to said guide surface; and means movable along said plane guide surface, and providing an edge extending along one of said directions, for the generation of cutting lines on said slab.

5. In apparatus for the determination of cutting planes in piezo-electric quartz: a light source; a substantially plane opaque light screen provided with two spaced apertures adjacent said light source, a guide member adjacent said light screen providing a plane reference surface extending beyond the side of said screen opposite said light source; and a member mounted for movement along said plane reference surface, the last named member having edges extending across said light screen and constituting at least portions of the sides of an isosceles triangle based in said plane reference surface, said sides extending in directions along which, for quartz of right-handed or left-handed polarity respectively, the piezo-electric frequency response of a quartz sample will undergo a minimum variation with temperature change, when said sample is in the form of an

etched slab with its major faces parallel to its Y and Z axes and is placed against said plane structural member and said apertures, and is of such thickness and so orientated that quadrilateral light dispersion patterns formed in said sample by light emerging from said apertures are interlocked by linear fusion of their adjacent sides.

6. In apparatus for the determination of cutting planes in piezo-electric quartz: a light source; a substantially plane opaque light screen provided with a plurality of spaced apertures adjacent said light source; a guide member adjacent said light screen providing a plane reference surface extending beyond the side of said screen opposite said light source in substantial parallelism with the plane defined by the light beams emerging from two of said apertures; and a member mounted for movement along said plane reference surface, the last named member having edges extending across said light screen and constituting at least portions of the sides of an isosceles triangle based in said plane reference surface and having a vertex angle of substantially four degrees.

7. In apparatus for the determination of cutting planes in piezo-electric quartz: a light source; a substantially plane opaque light screen provided with a plurality of spaced apertures adjacent said light source; a guide member adjacent said light screen providing a plane reference surface extending beyond the side of said screen opposite said light source in substantial parallelism with the plane defined by the light beams emerging from two of said apertures; and a member mounted for movement along said plane

35

reference surface, the last named member having edges extending across said light screen and constituting at least portions of the sides of an isosceles triangle based in said plane reference surface and having a vertex angle of substantially six degrees.

8. In apparatus for the determination of cutting planes in piezo-electric quartz: a light source; an opaque light screen provided with two spaced apertures adjacent said light source; a guide member adjacent said light screen providing a plane reference surface extending beyond the side of said screen opposite said light source in substantial parallelism with the plane defined by the light beams emerging from said apertures; a second guide member adjacent said light screen providing a second plane reference surface substantially perpendicular to the first mentioned reference surface; and a pair of cutting-plane determining means, each mounted for movement along a respective one of said reference surfaces, each of said means having at least one straight edge extending across said light screen, said edges extending in directions along which the piezo-electric frequency response of a quartz sample will undergo a minimum variation with temperature change, when said sample is in the form of an etched slab with its major faces parallel to its Y and Z axes and is placed against said light screen and said apertures, and is of such thickness and so orientated that quadrilateral light dispersion patterns formed in said sample by said light beams are interlocked by linear fusion of their adjacent sides.
